ARCHERY BOW

Dick M. Dixon, 475 E. 2nd S., Salem, Utah

Filed Jan. 21, 1963, Ser. No. 73,261

Term of patent 14 years

(Cl. D30—1)

FIG. 1

FIG. 2

FIG. 3

FIG. 4

FIG. 5

FIG. 6

FIGURE 1 is a plan view of an archery bow, showing my new design.

FIGURE 2 is a front elevation of my archery bow illustrated in plan view in FIGURE 1.

FIGURE 3 is a bottom view of my archery bow.

FIGURE 4 is a left side elevation of my archery bow as seen from the left of FIGURE 2.

FIGURE 5 is a rear elevational view thereof.

FIGURE 6 is a perspective view thereof.

I claim:

The ornamental design for an archery bow, substantially as shown.
